UNITED STATES PATENT OFFICE.

LOUISE B. LARIDON, OF NEW YORK, N. Y.

DESIGN FOR A SEWING-STAND.

40,861.

Specification for Design.

Patented Sept. 6, 1910.

Application filed July 5, 1910. Serial No. 570,502. Term of patent 7 years.

To all whom it may concern:

Be it known that I, LOUISE B. LARIDON, a citizen of the United States of America, residing in the city of New York, State of New York, have invented a new, original, and ornamental Design for Sewing-Stands, of which the following is a specification, reference being had to the accompanying drawing, forming part thereof.

The figure is a perspective view of the sewing stand, showing my new design.

I claim:

The ornamental design for a sewing stand, as shown.

LOUISE B. LARIDON.
